INTERNAL-COMBUSTION ENGINE.

1,357,152.

Specification of Letters Patent. Patented Oct. 26, 1920.

Application filed August 18, 1919. Serial No. 318,191.

To all whom it may concern:

Be it known that I, IRA M. DAVIDSON, a citizen of the United States, residing at Kansas City, in the county of Jackson and 5 State of Missouri, have invented certain new and useful Improvements in Internal-Combustion Engines, of which the following is a specification.

This invention relates to internal combustion engines and has for its object to produce an efficient engine of this character provided with a rotary distributor having a single channel for controlling the suction, compression and firing action and for co- 10 operating with an exhaust port in scavenging the engine. A further object is to provide an engine of the type outlined provided with a distributor and a valve interposed between the distributor and piston 15 for receiving the reactionary force of the explosion and with an exhaust port for the discharge of the flames at a point remote from the distributor to protect the latter and thereby minimize unequal expansion of 20 the same and consequently increase the efficiency of operation.

With these general objects in view the invention consists in certain novel and useful features of construction and organization 30 of parts as hereinafter described and claimed; and in order that it may be fully understood reference is to be had to the accompanying drawing, in which:

Figure 1, is a fragmentary central vertical section of a four cycle engine embodying the invention with the piston at the end of its firing or working stroke in full lines and in dotted lines at the end of its exhaust and scavenging stroke.

40 Fig. 2, is a similar but diagrammatic view showing the piston at the completion of its suction stroke, and in dotted lines at the beginning of its firing stroke.

Fig. 3, is a view similar to Fig. 1, but 45 showing the engine equipped with the ordinary type of puppet valve as distinguished from the sleeve type shown by Fig. 1.

In the said drawing, 1 indicates the cylinder of the engine provided with an exhaust 50 port 2. It is also provided with a chamber 3, an intake port 4, a scavenging port 5 and a passage 6, the latter communicating with the piston chamber at its outer end. Fitting snugly in the chamber 3 is a rotating distributor 7 adapted to be driven from the

cam shaft in the customary or any preferred manner, and provided with a single channel 8 for successive communication with the intake port, the scavenging port and said passage 6. The head of the cylinder 60 constitutes a valve seat 9 for a puppet valve whereby communication between the piston chamber and passage 6, is controlled. In the preferred construction as shown by Fig. 1, the puppet valve 10 is in the form of 65 a hollow cylinder open at both ends and seated at its upper extremity against the underside of the head, and said head is provided with one or more openings 11 for the reception of one or more spark plugs, not 70 shown, it being noted that as the open end of the valve 10 is of large area, it is practicable to utilize a plurality of spark plugs, if desired, for the better propagation of combustion and the consequently more reliable and efficient operation of the engine. With the other type of engine, as shown by Fig. 3, it is hardly practicable to employ more than one spark plug in a multicylinder 75 engine, the spark plug opening in said construction being shown at one end of the cylinder as at 12.

In both cases the puppet valve is opened by the action of a driven cam 13, the same being located at the lower end of the valve 85 and operating on a lateral projection 14 thereof, in the construction shown by Fig. 1. In the other construction the puppet valve is provided with a central stem 15 extending up through a passage 15^a in the head, 90 which passage is enlarged to receive a spring 16 bearing at its lower end upon the head and at its upper end upon a cap 17 fitting on the stem and adapted for engagement and depression by the cam 13 once in each revolution thereof. In the preferred construction the sleeve valve 10 is engaged at its inner end by a spring 18 bearing against a flanged ring 19 or the like, rigid with and depending from the inner end of the cylinder, the spring in both cases being adapted to seat the valve quickly when not engaged by the cam.

The sleeve valve is provided with a lateral port 20 which is in communication with the 105 exhaust port 2 of the cylinder when the said valve is closed, and said port 20 is at times closed by the piston 21 which fits with a substantially gas-tight relation in the sleeve valve, it being understood that the pressure 110

- of the spring on the sleeve valve will be sufficient to guard against opening movement of the sleeve valve under the frictional engagement of the inwardly moving piston
- 5 21. With the construction shown by Fig. 3, the piston operates directly within the cylinder as customary and hence has no tendency through friction to effect the opening of the overlying puppet valve.
- 10 21. The preferred construction possesses one distinct advantage over the other construction in that it will exert suctional action for the full stroke of the piston as hereinafter more particularly pointed out, whereas with
- 15 21. the construction shown by Fig. 3, there will be a drop in pressure just before the full suctional stroke of the piston is completed, because it begins to uncover the exhaust port 2 just before such stroke is ended.
- 20 21. The operation of the preferred construction is, as follows: As the firing or working stroke is ended, the flame and approximately seventy per cent. of the hot gases escape through the registering ports 20 and 2, and by
- 25 21. the time the piston has bridged said exhaust port on its return or scavenging stroke, the sleeve valve has been opened by the cam, and in turn has bridged said exhaust port and therefore closed the same, the continued re-
- 30 21. turn or scavenging stroke of the piston forcing the remainder of the gases through the open upper end of the sleeve valve, passage 6 and the channel 8 of the distributor, the channel at this time establishing but gradu-
- 35 21. ally cutting down communication between passage 6 and the scavenging port 5. The cam which opened the sleeve valve as ex- plained, holds it open until the piston has made its following or suction stroke, and as
- 40 21. such stroke ends the cam passes out of engagement with the valve and the spring instantly closes the same, the distributor oc- cupying the position shown in dotted lines
- 45 21. Fig. 1, at the completion of the scavenging stroke, that is to say occupying a position in which it has started to open communica-
- 50 21. tion between the intake port and the passage 6. At the completion of the suction stroke the distributor occupies the position shown
- 55 21. by full lines in Fig. 2, and as the compres- sion stroke ends, the channel of the distributor occupies the position shown by dotted lines Fig. 2, it being noted that at this time the sleeve valve is closed and in
- 60 21. conjunction with the head of the cylinder sustains the compression of the charge of gas ready for ignition.
- 65 21. It will be noted that as the valve is held in its innermost position, that is in a position where it bridges and therefore closes the exhaust port 2, during the suction stroke, there is no waste of fresh gas. With the construction shown by Fig. 1, there is a small wastage of the fresh gas during the fraction
- 65 21. of time between the inward movement of

the piston past port 2 and the reclosure of said port by the piston upon its ensuing or compression stroke.

By the use of a rotary distributor pre- cision in opening and closing at all speeds 70 is obtained and by protecting said distribu- ter through the provision of the main ex- haust port 2 and the puppet valve, all flame and the greater proportion of the hot gases are discharged from the cylinder remote 75 from the distributor and as a result unequal heating and expansion of the latter is mini- mized. It will, furthermore, be noted that the valve of both constructions can be opened easily as at the time they are opened by the 80 cam they are not opposed by internal pres- sure.

A construction such as described in which the distributor is protected from the flames and greater volume of the hot gases, is also 85 desirable as trouble due to the deposit of carbon on the distributor or seat thereof is largely eliminated, and this being true danger of misfiring is lessened and the ne- cessity of comparatively frequent grinding 90 is obviated.

The use of rotary or oscillating valves has been contemplated but as far as applicant is aware no such construction has proven 95 efficient and satisfactory.

While the drawing shows and the specifi- cation refers to a single cylinder and its equipment, it is obvious that the invention 100 contemplates multi-cylinder motors, and that in such motors it is practicable to em- ploy a single distributor provided with a channel for each cylinder.

From the above description it will be ap- parent that I have produced an internal 105 combustion engine embodying a reciproca- tory piston and a rotary distributor, which will operate efficiently at any speed and in which the distributor has a self-cleaning ac- tion by shearing engagement with the edges 110 of the ports over which it operates, and while I have illustrated and described the preferred and one other type of construction of the engine, it is apparent that it is sus- ceptible of modification without departing 115 from the spirit and scope or sacrificing any of the advantages of the appended claims.

I claim:

1. In an internal combustion engine, the combination of a cylinder having an exhaust port at a point intermediate its ends, a cylind- 120 rical chamber, having intake and scaveng- ing ports communicating therewith and a passage connecting said chamber with the outer end of the piston chamber, a valve nor- mally closing communication between the 125 piston chamber and said passage, a rotary distributor fitting in said chamber and pro- vided with a channel for establishing com- munication between the passage and the intake port and the scavenging port and said 130

- passage in each revolution, a piston for reciprocating in the cylinder and for opening the exhaust port thereof, on each in-stroke, means for unseating said valve on the completion of the working or firing stroke of the piston and for holding said valve open until the next outward or suction stroke of the piston has occurred, said valve being of sleeve form and externally embracing the piston, and provided with an exhaust port normally registering with the exhaust port of the cylinder and when fully unseated, out of register with said last named port.
2. In an internal combustion engine, the combination of a cylinder having an exhaust port at a point intermediate its ends, a cylindrical chamber, having intake and scavenging ports communicating therewith and a passage connecting said chamber with the outer end of the piston chamber, a yieldingly closed puppet valve normally closing communication between the piston chamber and said passage, a rotary distributor fitting in said chamber and provided with a channel for establishing communication between the passage and the intake port and the scavenging port and said passage in each revolution, a piston for reciprocating in the cylinder and for opening the exhaust port thereof on each in-stroke, means for unseating said valve on the completion of the working or firing stroke of the piston and for holding said valve open until the next outward or suction stroke of the piston has occurred, said valve being of sleeve form and externally embracing the piston, and provided with an exhaust port normally registering with the exhaust port of the cylinder and when fully unseated, out of register with said last named port.
- 20 In testimony whereof I affix my signature.
IR A M. DAVIDSON.
